Primary Examiner — Mary Ann Calabrese*Assistant Examiner* — Natalya M Rapundalo(74) *Attorney, Agent, or Firm* — Wolf, Greenfield & Sacks, P.C.(57) **CLAIM**

The ornamental design for a beverage cartridge, as shown and described.

DESCRIPTION

FIG. 1 is a top, rear, and left side perspective view of a beverage cartridge showing our new design;

FIG. 2 is a top, front, and right side perspective view thereof; and,

FIG. 3 is a top plan view thereof.

The dot-dash broken lines illustrate boundaries of the claim and form no part of the claimed design. The dash-dot broken lines illustrate portions of the beverage cartridge that form no part of the claimed design.

1 Claim, 3 Drawing Sheets(56)
